UNITED STATES PATENT OFFICE.

ALDIN VAN. WALTERS, OF GALION, OHIO.

BOILER-FLUE.

No. 823,907.

Specification of Letters Patent.

Patented June 19, 1906.

Application filed March 15, 1906. Serial No. 306,157.

To all whom it may concern:

Be it known that I, ALDIN VAN. WALTERS, a citizen of the United States, and a resident of Galion, in the county of Crawford and State 5 of Ohio, have invented a new and Improved Boiler-Flue, of which the following is a full, clear, and exact description.

This invention relates to flues or tubes as constructed in modern tubular boilers, and is especially useful in connection with steam-boilers of the locomotive or marine type.

The object of the invention is to provide a strong, efficient, and durable boiler-tube which effects a lasting and hermetically-tight 15 joint between the tube and the flue-sheets, which can be easily removed and replaced when worn out, and which tends to decrease the troublesome encrustation encountered in steam-boilers.

20 The invention consists in the construction and combination of parts, which will be set forth hereinafter, and particularly pointed out in the claims.

Reference is to be had to the accompanying 25 drawings, which illustrate as an example the preferred embodiment of my invention, in which drawings similar characters of reference indicate like parts in the several views, and in which—

30 Figure 1 is a longitudinal cross-section of my invention with a portion broken away. Fig. 2 is an elevation of that part of the tube which fits into the back flue-sheet; and Fig. 3 is an inner view of a portion of the back 35 flue-sheet, showing the opening for the end of the tube.

Referring more particularly to the drawings, 1 represents the front and 2 the back flue-sheet of a boiler. The flue or boiler-tube 3, (shown partially broken away in the drawings,) is secured in orifices in the flue-sheets and permits the passage of the gases of combustion from the combustion-chamber to the smoke-box. The tube 3 near its rear 45 extremity is provided with an external annular flange 4, disposed concentrically around the flue-body and having a rounded rim 5. This rim 5 is provided internally and externally with threads 6 and 7, which are adapted 50 to engage with corresponding threads 9 and 10 in a circular recess or groove 8, formed in the back flue-sheet 2 around an orifice 11 for the flue. The forward end 12 of the tube flares or widens outwardly to a diameter 55 slightly greater than that of the extension 4, so that the latter will pass through the orifice

for this larger end of the tube in the front flue-sheet, thus permitting the putting in place or removal of the flue through this opening.

In placing the tube in the boiler it is inserted through the opening in the front flue-sheet and the rear end is inserted in the orifice drilled for this purpose in the back flue-sheet. The threaded rim of the shoulder 4 is then tightly screwed into the recess 8 and the end 12 of the tube is expanded and turned over into a bead 13 in the usual manner. The forward outwardly-tapered end 14 of the tube is secured in the opening in the front 70 flue-sheet by the known method of expanding and turning the end over into a bead 15.

As the gases of combustion are at the highest temperature on entering the tubes from the combustion-chamber, the ends of 75 the tubes which first come in contact with the gases are more liable to injury therefrom. Consequently the reinforcement provided by the threaded shoulder 4 is of great value, and even should the bead 13 be burned off 80 there would be no leakage around the end of the tube, as the rim 6 of the extension 4 forms a tight joint with the threaded groove 8. There is no danger of burning out this joint, as the shoulder 4 is at all times surrounded 85 by water. In using boiler-tubes of this type the spacing will be greater, and as the tubes will consequently be farther apart the accumulation of encrustations will be retarded.

Having thus described the preferred embodiment of my invention, what I claim as new, and desire to secure by Letters Patent, is—

1. A boiler-flue comprising a tubular body having an annular concentric flange near one 95 end, means for securing said flange to the inner side of the flue-sheet, and extremities adapted to attach in openings in the flue-sheets.

2. A boiler-flue comprising a tubular body 100 having an annular concentric flange near one end provided with a threaded rim adapted to engage with a threaded groove in the flue-sheet, and extremities adapted to be expanded in openings in the flue-sheets.

3. A boiler-flue comprising a tubular body, an exterior concentric flange having an annular rim provided externally and internally with screw-threads adapted to engage with a correspondingly-threaded groove in the flue-sheet, and extremities adapted to be expanded in openings in the flue-sheets.

4. A boiler-flue comprising a tubular body, an exterior concentric flange having a threaded rim adapted to engage with a correspondingly-threaded groove in the rear flue-sheet, and extremities adapted to be expanded in openings in the flue-sheets, one of said extremities flaring outwardly and secured in an opening in the front flue-sheet.
5. The combination with a boiler having flue-sheets provided with openings and a threaded groove on the inner side of one of said flue-sheets, of a flue having a tubular
- body, an annular flange near one end having a threaded rim adapted to engage with said groove, and extremities adapted to be expanded in said openings.
- In testimony whereof I have signed my name to this specification in the presence of two subscribing witnesses.

ALDIN VAN. WALTERS.
